UNITED STATES PATENT OFFICE.

WILBUR F. OSBORNE, OF ANSONIA, CONNECTICUT.

DESIGN FOR SUSPENDER-ENDS.

SPECIFICATION forming part of Design No. 11,684, dated March 16, 1880.

Application filed October 8, 1879. Term of patent 34 years.

To all whom it may concern:

Be it known that I, WILBUR F. OSBORNE, of Ansonia, in the county of New Haven, State of Connecticut, have invented a new and original Design for Suspender-Ends; and I do hereby declare that the following is a full, clear, and exact description.

The present design has for its object to give a highly-ornamental and æsthetic appearance to suspender-ends by means of a series of alternating checks and reticulations and an ornamental border at the edges and button-holes.

The drawing represents a plan view of my design.

The letter A indicates the body of the suspender-end, which is composed of a flat strip having a series of checks, *a*, and reticulations *b* on one or both sides, alternating, as shown, so as to resemble basket-work, and extending from one extremity to the other of the suspender-end.

The letter B indicates an ornamental rounded selvaged border extending along the edges of the body of the suspender-end, and C indicates the button-holes, the edges of which have 25 an ornamental rounded selvaged border, *c*, similar to the border at the edges of the body.

What I claim is—

The design for a suspender-end, the same consisting of the flat strip of textile material 30 of uniform width throughout, having the series of alternating rectangular checks *a* and the openings or spaces *b*, parallel with each other, and extending transversely across the strip, and having the rounded border B, all as 35 herein shown.

In testimony whereof I have hereunto set my hand this 3d day of October, A. D. 1879.

WILBUR F. OSBORNE.

In presence of—

FRANKLIN BURTON,
ADOLPH W. KING.
